AERIAL BOMB

Harry G. Lankford, Wichita, Kans.

Application September 20, 1954, Serial No. 456,972

5 Claims. (Cl. 102—2)

This invention relates to projectiles. In a more specific aspect, this invention relates to aerial bombs carrying a bursting charge which is exploded by a fuse upon impact with an object or the ground. In a still more specific aspect, this invention relates to new ejecting means. In yet a more specific aspect, this invention relates to new means for ejecting the fuse cover caps of an aerial bomb so that the fuse may be activated while falling through the atmosphere, that is, so that the motion of the bomb and fuse through the air results in turning the propeller activation means of the fuse to activate the fuse so that it will explode the bursting charge of the bomb upon impact. In still another specific aspect, this invention relates to new bomb projectile means, particularly to new aerial bomb case means.

Aerial bombs have long been known in the art, such bombs carrying a bursting charge of explosives such as nitroglycerin or trinitrotoluene, napalm bombs containing such as highly inflammable hydrocarbon materials, or bombs containing inflammable metals such as magnesium and phosphorous, and the like. It is known to explode these bombs by fuses carried or contained in the nose and/or tail portions of the bomb, and the common or usual fuse for an aerial bomb is activated so that it will explode the bomb on impact by the expedient of means turned by a small propeller on the fuse, such propeller being turned as the result of the bomb falling by the force of gravity from an aircraft through the air. These aerial bombs have a nose cap and a tail cone covering the bomb fuses, which in most instances are used on both ends of the bomb, and ejecting means are used to separately eject the nose cap and tail cone covers for the fuses so that when the bomb falls through the air the air can come in contact with the propeller and turn same and activate the fuses. For safety sake, arming means in the form of an arming wire has been used on the bombs to lock the propeller against turning until it is desired to release same prior to dropping the bomb, and it is known to incorporate such arming wire into the activating means for ejecting the end portion covers for the fuses. Aerial bomb cases have been constructed in end and center section members for ease of construction, shipping, and the like, and means have been incorporated with such to hang the bombs from an aircraft from which they are released to drop by the force of gravity. And, clamping or holding means to hold the end sections mounted on the center section are known in the art, such being operable from the outside of the bomb and holding the sections together on the inside of the bomb case, this being desirable from a standpoint of streamlining the bomb case. Preferred new clamping and holding means of my invention for my new bomb case as disclosed and depicted in use in this disclosure are disclosed and claimed in my co-pending application Serial No. 441,610, filed July 6, 1954. It is projectiles of the aerial bomb type with which my invention is particularly concerned, and the new ejecting means of my invention

2

is especially adapted to eject the fuse covers of aerial bombs.

I have invented new projectile case means which has a first section having structure therewith to mount a fuse. 5 A cover for the fuse is ejectably mountable on the first section. Bracket means is mounted on this first section and such has means therewith to receive the arming means of the projectile. The new projectile case of my invention has a spring loaded ejecting means which is 10 releasable by the arming means, such being adapted to eject the cover of the fuse. The bracket means which is mounted on the first section holds the ejecting means in loaded position when the arming means is in place, and this ejecting means functions to eject the fuse cover from the first section upon removal of the arming means. The bomb case of my invention has at least one other section which is mountable on the first section. The sections of the new bomb case are preferably held together on the inside of the bomb case by the new spring 15 loaded clamp means of my invention, referred to hereinbefore. These clamping means are operable from without the bomb case, and these clamping means hold the sections together when the clamps are in their clamping position. I prefer that the new fuse cover ejecting means 20 of my invention be used with the new bomb case of my invention. However, the new fuse cover ejecting means of my invention can be used with other projectiles, and the like, particularly aerial bombs of different structure than that of mine. The new ejecting means for the fuse 25 cover of a bomb of my invention has a bracket mounted on the bomb, and this bracket has means to receive the bomb arming means. The new means has a spring loaded ejecting means which is releasable for action by these bomb arming means, and this ejecting means functions 30 to throw off or eject the cover for the fuse. The bracket means is adapted and functions to hold the ejecting means in loaded position when the arming means of the bomb is in place, and the ejecting means functions and is adapted to throw off and eject the fuse cover from 35 the bomb upon removal of the arming means so that the fuse of the bomb may be activated.

The new projectile case means of my invention because of its new structure has many advantages over the projectile cases of the prior art. It is easier to manufacture, ship and store, and in particular it is much easier and faster to assemble. The structure of the new projectile case of my invention results in a stronger projectile case with less weight. And, it has been found that the bomb is more reliable and safer to handle and use. The new ejecting means for the fuse covers of a projectile is a great step forward in the art. I have eliminated a substantial number of parts and operations in making the ejecting means in relation to those of the prior art, and the ejecting means of my invention is far superior in 40 ease of operation and reliability than those means known and used before my invention.

It is an object of my invention to provide new projectile means.

It is another object of my invention to provide new aerial bomb case means.

Another object of my invention is to provide new ejecting means for the fuse covers of projectiles.

Still another object of my invention is to provide new ejecting means which is particularly desirably used to eject or throw off the fuse covers of an aerial bomb so that air currents will turn the propeller means of the fuse to activate the fuse when the bomb falls through the air by the force of gravity from an aircraft.

Yet other objects of my invention are to provide new aerial bomb case means of great structural strength which are relatively light in weight and which are easy and

economical to manufacture, and convenient and safe to use, and new fuse cover ejecting means for projectiles which are simple and reliable in operation, and easy and economical to manufacture.

Other objects and advantages of the new projectile case means and ejecting means of my invention will become apparent to those skilled in the art upon reading this disclosure.

Drawings accompany and are a part of this disclosure. Such drawings depict preferred specific embodiments of the new projectile case means and ejection means of my invention, and it is to be understood that such drawings are not to unduly limit the scope of my invention.

In the drawings,

Fig. 1 is a longitudinal elevation view of a preferred specific embodiment of the new aerial bomb case of my invention employing a preferred specific embodiment of the new ejecting means of my invention for ejecting or throwing off the nose cap and tail cone at the ends of the bomb which cover the propeller activated fuses to explode the bursting charge of the bomb upon impact.

Fig. 2 is an enlarged elevation view taken on line 2—2 of Fig. 1 with the nose cap cut away, of the nose fuse of the bomb of Fig. 1 and showing in side elevation an enlarged detailed view of the new ejecting means of my invention in loaded position with the arming wire for the nose fuse of the bomb in place.

Fig. 3 is a perspective view of the plate member of my new ejecting means which is mounted on and forms a part of the bracket means of my new ejecting means.

Fig. 4 is a perspective view of the portion of the bracket assembly of my new ejecting means which is mounted on the nose bulkhead of the bomb, and on the tail bulkhead.

Fig. 5 is a perspective view taken on line 5—5 of Fig. 1 showing preferred clamping means used to hold sections of the new bomb case of my invention together, such clamping means being disclosed and claimed in my co-pending application as set forth hereinbefore.

Fig. 6 is an exploded view of these preferred clamping means.

Fig. 7 is an elevation view taken on line 7—7 of Fig. 1 with the bomb shell cut away and showing preferred specific bulkhead and hanger means of the new aerial bomb case of my invention.

Fig. 8 is a view taken on line 8—8 of Fig. 7.

Fig. 9 is a perspective view of the preferred specific embodiment of the new ejecting means of my invention shown mounted in loaded position on the tail end bulkhead of the new bomb case of my invention as shown in Fig. 1 and in the absence of the tail bomb fuse. The nose cap and tail cone ejecting means preferred and shown in the drawings are identical.

Fig. 10 is a perspective view partly cut away and partly in cross section of the tail cone of the new bomb case of my invention showing in detail preferred latch means to along with my new ejecting means hold the nose cap and tail cone on the ends of the bomb case.

Fig. 11 is an elevation view partly in cross section and partly cut away of the means to fill the bomb in the nose section thereof, including the removable cap to seal the filling aperture through the side of the nose section.

Following is a discussion and description of my invention. Such discussion and description is made with reference to the drawings whereon the same reference numerals are used to indicate the same or similar parts or structure. The discussion and description is of preferred specific embodiments of the new projectile case and ejecting means of my invention, and it is to be understood that the discussion and description is not to unduly limit the scope of my invention.

The new bomb case of my invention depicted in the drawings has a hollow, frusto-conoidal nose section 13, a hollow, frusto-conoidal tail section 15 and a hollow, cylindrical center section 17. These have a shell prefer-

ably of metal, such as aluminum or magnesium, attached to the bulkhead and supporting members of the bomb case in any suitable manner such as by rivets or welding the shell members to the bulkhead and supporting structure. The end sections 13 and 15 are disengageably mounted on the center section 17 by spring loaded clamps 19 which overlap when in mounted position a raised portion 21 of the end sections and an opposite raised portion 23 of the center section 17, such raised portion 23 being the same on each end of the center section 17. These circumferential raised portions support the bomb case and provide the holds for clamp bodies 19. Bolts 25 passing through raised portions 21 and threadedly secured to clamp bodies 19 are used to position the clamp bodies 19 in open or closed position, that is, when in open position the clamp bodies are spaced from raised portions 21 of the end sections so that they can receive for mounting the center section 17. Bolts 25 are tightened to bring the clamp bodies 19 into contact with the raised portions 21 and 23 to tightly secure the bomb sections together. An important feature of the preferred clamp means is the leaf spring 27 which spring loads the clamp and maintains the clamp body spaced from raised portion 21 so that the ends of center section 17 can be received when desired no matter what position the end sections 13 and 15 are in. The hole in raised portion 21 for bolt 25 is preferably countersunk so that the top of the head of bolt 25 will be even with or below the shell surface and thus streamline the bomb case. These clamp means have been found very desirable in use, and are disclosed and claimed in my co-pending application referred to hereinbefore. An O-ring seal 29 in the slot of raised portion 23 is preferably used to provide a tight seal between the end sections 13 and 15 and the center section 17.

The center section 17 of the new bomb case of my invention preferably has bulkheads 31 transversely mounted therein. These bulkheads 31 strengthen and support the bomb case and provide attachment means for hangers 33 which are used to attach the bomb to an aircraft for carrying to a target, and which are used in handling the bomb during bursting charge loading and during loading into the aircraft. The bulkhead and supporting assembly preferably has upper longitudinal plate means 35 forming a part of the upper super structure, forming a part of the attachment means for the hanger 33 and providing mounting means for the transverse bulkheads 31. The outer shell of the center section 17 of the bomb case is preferably reinforced by liner 37 which forms a portion of the bulkhead super structure. I have found it preferable and desirable to form the bomb super structure and bulkheads 31 out of light weight metals such as aluminum or magnesium.

The nose section 13 of my new bomb case has an aperture therein through which the bomb is charged as shown in Figs. 1 and 11. A removable cap 39 for sealing the charging aperture through the side of section 13 is desirably employed. A conduit 41 extends inside nose section 13 through nose bulkhead 43 and the side of nose section 13 near the base thereof, and a like conduit 41 extends through the tail bulkhead 45 and the side of tail section 15 near the base thereof. These conduits 41 carry arming wires 47 which in position lead to fuses 49, one on each end of the bomb. Conduits 41 are rigidly mounted in end sections 13 and 15 in any suitable manner such as by welding. A hollow nose cap 51 covers the nose end of the bomb case and fuse 49, and a hollow tail cone 53 covers the tail end of the bomb and fuse 49 mounted thereon. Nose cap 51 and tail cone 53 are ejected or cast off by the ejecting means of my invention when the bomb is dropped from an aircraft so that upon falling through the air propellers 55 will be turned to operate mechanism within fuse 49 to activate same so that the bursting charge of the bomb will be exploded when the bomb hits an object or the ground.

The ejecting means of my invention is the same for each end of the bomb and has a like bracket 57 mounted on bulkheads 43 and 45, respectively. This bracket is preferably rigidly mounted in any suitable manner such as by welding. The upper face portion of the bracket 57 has grooves 59 in the end portions thereof and an eye portion 61 with the eye thereof in alignment with the grooves to receive arming wire 47. An arming plate member 63 having grooves 65 in the end portions of the face thereof and an aperture 67 in the middle portion of the face thereof is ejectably mounted on bracket member 57 with eye member 61 projecting through aperture 67 and the raised portions resulting from grooves 65 fitting in grooves 59. The arming wire 47 passes through conduit 41 through grooves 65 and the eye formed by members 57 and 63 through groove 59 in the upper portion of bracket 57 and through a hole in the shaft for propeller 55. The arming wire prevents propeller 55 from turning until arming wire 47 is removed. The side portions of bracket members 57 have eye members 69 to receive the inner ends of the spring loaded ejecting arm 71. The ejector arm or spring is preferably made of spring wire material and is spring loaded by spiral springs 73 which are integral therewith. The outer end portion 75 of the ejector arm 71 fits into a slot 77 in the nose cap 51 and tail cone 53. When the arming wire 41 is in place and the spring arm 71 is mounted as shown in Figs. 2 and 9, this outer end portion 75 serves to hold the nose cap 51 and tail cone 53 on their respective ends of the bomb, and when in action to eject the nose cap and tail cone this portion 75 of ejector arm 71 contacts the nose cap 51 and tail cone 53 to tilt them outwardly away from bulkheads 43 and 45, respectively. With the arming wire in place, feet portions 79 of plate members 63 hold down the ejector arm 71 in spring loaded position. Safety means are provided to aid in handling the charged bombs in storage, aircraft loading, etc. This means comprising a safety pin 81 which passes through corresponding holes 83 in the side portions of bracket member 57 and plate member 63. This provides for locking the ejection arm in loaded position even though the arming wire is not in place as shown in Fig. 2. This safety pin 81 is removed before placing the nose cap 51 and tail cone 53 on their respective ends of the bomb in preparation for arming the bomb by withdrawing arming wires 47.

To aid in holding the nose cap 51 and tail cone 53 on their respective bomb ends, spring loaded latch means is used, such being oppositely disposed from end portion 75 of ejector arm 71 and the slot 77 into which it fits. These latch means are preferably a spring loaded arm or hook spring 85 attached to the inside of the end covers in one end by rivet means 86 and projecting out through a hole in the covers in the other end portion. A catch 87 is mounted on the bulkheads 43 and 45 to receive the hook portion of latch arm 85. I have found that in operation nose cap 51 and tail cone 53 fall easily and cleanly off the bomb upon operation of the ejecting arm 71, and the covers 51 and 53 are easily installed by fitting slot 77 over portion 75 of arm 71 and snapping latch means 85 into place on catch 87.

The operation of the new ejecting means of my invention is as follows. With the pin 81 removed and the arming wire 47 in place as shown in Fig. 2, the ejecting mechanism is operated by withdrawing arming wires 47 out of the end sections of the bomb. The arming wires 47 inside the bomb first are withdrawn from the shafts of propellers 55 releasing them for subsequent rotation. Then as arming wires 47 are further withdrawn, plate members 63 are freed and forced outwardly by the tension on spring arms 71. Likewise, the springs through end portions 75 in contact with the covers 51 and 53 throw them outwardly to eject them from the ends of the bomb. As the bomb falls the propellers 55 in contact and moving through the air rotate activating

the fuses and arming the bomb so that the bursting charge will explode upon the bomb hitting the ground or an object.

The bomb case and means shown is particularly preferred for a fire bomb with a fuse on either end. However, as one skilled in the art will readily see, the ejecting means can equally satisfactorily be used with a bomb employing only a single fuse in the nose end thereof.

The new nose and tail assemblies of the bomb means 10 of my invention are decidedly advantageous over the presently used assemblies from the standpoint of simplicity and cost as well as reliability and ease in use. Actual facts and figures show that the nose bulkhead and parts forward of the new nose assembly of my invention are 7 in number as compared to 31 in the usual prior art assembly, excluding the nose cap and fuse which are the same in each case, and the number of operations to assemble is 14 in my new means as compared to 53 in the prior art nose assembly. In regard to the tail 15 assembly and parts aft, the comparable figures are 7 parts and 14 operations in the new assembly of my invention, and 23 parts and 41 operations in the prior art assembly.

Clearly the new means of my invention is a great 20 step forward in the art.

As will be evident to those skilled in the art, various 25 modifications of my invention can be made, or followed, in the light of this disclosure and discussion, without departing from the spirit or scope of the disclosure or 30 from the scope of the claims.

I claim:

1. Means for ejecting a fuse cover of a bomb having an arming wire to activate said fuse, which comprises, in 35 combination, bracket means mounted on said bomb, a spring loadable arm member, said arm member mountable and positionable to contact said cover to eject said cover upon release of said arm member, an ejectable retaining member mountable on said bracket means, said retaining member when mounted having portions adapted 40 to contact said arm member to hold same in loaded position, said retaining member and bracket means having means to receive said arming wire to hold said retaining member on said bracket and said spring loadable arm member in said loaded position, and said means for ejecting adapted to eject said cover from said bomb upon 45 removal of said arming wire from said bracket means and retaining member.

2. Means for ejecting a fuse cover of a bomb having removable arming means to activate said fuse, which 50 comprises, in combination, bracket means mounted on said bomb having means to receive said arming means, spring loaded ejecting means releasable by said arming means and operable to eject said cover, said bracket means having a releasable member having portions which 55 when mounted contact said ejecting means to hold said ejecting means in loaded position and having other portions which receive said arming means to mount said releasable member on the rest of said bracket means and said bracket means being adapted to hold said ejecting means in loaded position with said arming means in place, and said means for ejecting being adapted to eject said cover from said bomb upon removal of said arming means.

3. Means for an elongated aerial bomb for ejecting an 65 end cover thereof having a slot therein, such aerial bomb being explodable on impact by a fuse mounted on an end portion thereof which is covered by said end cover, such fuse having activation means including and operable by a propeller which turns as said bomb falls through the 70 atmosphere, which comprises, in combination: an arming wire; a bracket having side portions and a face portion rigidly mounted on said end portion of said bomb to project therefrom, said bracket having a groove in the end portions of said face portion and an eye in the middle portion of said face portion to receive said arming wire.

and opposite eye members on said side portions; an arm member formed of wire mounted on said bracket with the ends of said wire arm member mounted in said side eye members, said arm member having spiral spring means integrally formed therewith, being spring loadable and the outer portions thereof adapted to fit into said slot in said end cover to hold same on said bomb and to eject said end cover from said bomb when said spring is released; a plate member mounted on said bracket member, said plate member having side portions, feet portions and a face portion with grooves in the end portions corresponding to said bracket grooves to receive said arming wire, and an aperture in the middle portion to receive the face portion of said bracket member having said eye, said plate member adapted to fit over said bracket and said feet adapted to contact said spring loaded arm member on each side of said bracket to keep same loaded and prevent ejection of said cover when said arming wire is in place in said grooves of said plate and bracket and through the eye of said bracket projecting through said plate member aperture; spring loaded latch means mounted on said end cover opposite said slot contactable with a catch mounted on the end portion of said bomb to hold said end cover on said bomb prior to ejection; a safety pin; apertures through said side portions of said bracket and plate member to receive said safety pin to hold said bracket and plate together in the absence of said arming wire; and said means for ejecting adapted to eject said end cover from said bomb upon removal of said arming wire from said bracket and plate in the absence of said safety pin.

4. In an aerial bomb having an end portion, a fuse mounted on said end portion, an end cover for said fuse and an arming wire, means for ejecting said end cover so that said fuse can be activated, which comprises, in combination: a bracket mounted on said end portion of said bomb; an ejecting arm member mounted on said bracket, said ejecting arm member having spiral spring means integral therewith and adapted in its outer portion to contact said end cover to hold same on said end portion of said bomb when said spring means is held in force exerting position and to eject said cover from said bomb when said spring means is released; a plate member mountable on said bracket, said plate member having portions positionable when mounted to contact and hold said arm member when such is in said force exerting position and said plate and bracket when mounted together having

5

eye means positioned to receive said arming wire to hold said plate member and bracket together and said arm member in said force exerting position with said cover on said bomb; latch means mounted on said cover and said end portion of said bomb adapted to hold said cover on said bomb when said ejecting arm member is in said force exerting position and adapted to release said cover when said ejecting arm member ejects said cover; removable safety pin means operably mountable on said plate and bracket to hold said plate in mounted position on said bracket in the absence of said arming wire; and said means for ejecting adapted to eject said cover from said bomb upon removal of said arming wire from said bracket and plate in the absence of said safety pin means.

5. In an aerial bomb having an end portion, a fuse mountable on said end portion, an arming wire for said fuse, an ejectable end cover for said end portion, and means for ejecting said end cover, which comprises, in combination, bracket means mounted on said end portion of said bomb, a spring loadable arm member mounted on said bracket, the outer portion of said arm member positionable to contact said cover to hold same on said end portion of said bomb when said arm member is spring loaded and said arm member operable to eject said cover from said bomb upon release of said arm member, a retaining member mountable on said bracket means and ejectable by said arm member, said retaining member when mounted contacting and holding said arm member in loaded position, and said retaining member and bracket means being positionable to receive said arming wire to hold said retaining member on said bracket and said arm member in said loaded position with said cover on said bomb; latch means mountable on said end portion of said bomb and positionable to hold said cover on said end portion of said bomb when said arm member is in loaded position; and said means for ejecting said end cover adapted to eject said cover from said bomb upon removal of said arming wire from said bracket means and retaining member.
